BOTTLE MOTION MECHANISM FOR ROTARY
BOTTLE FILLING MACHINESJames Chignell, Hall Green, Birmingham,
EnglandApplication March 21, 1933, Serial No. 661,876
In Great Britain March 22, 1932

7 Claims. (Cl. 226—96)

This invention comprises improvements connected with bottle motion mechanism for rotary bottle filling machines and refers to that type in which the bottle seat has been actuated by a 5 cam for the purpose of raising the bottle positioned on the seat into contact with the filling head.

Prior to this invention, in machines wherein a cam actuated bottle seat has been provided, the lift provided for the bottle seat was of a comparatively short length, as the filling tubes in the machine were usually of the curved type, and the bottles were threaded on said tubes and positioned on the bottle seat by hand. The bottle 15 seats were then raised by the cam motion to seat the bottles on the filling head during the filling operation.

The object of the present invention is particularly to provide a cam actuated bottle seat which is adapted for use in connection with apparatus wherein the bottles are automatically fed on the bottling machine and also automatically removed therefrom; in which case it is necessary for the bottles to be lowered clear of the filling tubes 20 which have to be straight and reach close to the bottom of the bottle for efficient filling.

Referring to the drawings:

Figure 1 is a vertical section of a general arrangement of a rotary bottle filling machine with the bottle motion mechanism according to this invention.

Figure 2 is an elevation of the cross-head at the bottom of its travel.

Figure 3 is a side elevation partly in section of the cross-head at the top of its travel, with a hook for retaining the cross-head in its raised position.

Figure 4 is the development of the cam for operating the cross-heads.

Figure 5 is an elevation of the release cam.

Figure 6 is a plan of said release cam.

Figure 7 is a side elevation of the cross-head control levers, whilst,

Figure 8 is an end view of same.

In carrying the present invention into practice as shown upon the accompanying drawings, the rotary filler is of the well known type in which the filling head is rotated in the usual manner. The bottle seat 10 is mounted on the end of the 45 rod 11, whilst the lower end of said rod 11 is connected to the lower part 12 of the split cross-head; the upper part 13 of said cross-head is connected to the lower part 12 by means of the tension springs 14.

The upper part of the cross-head is provided

with a pin 15 on which is mounted a roller 16 which engages the cam 17 as shown in Figure 4, for raising and lowering the bottle seat 10. The cross-head is mounted between a pair of guide rods 18, 19, which are secured at their lower ends to the framework 20 of the machine, whilst at the upper ends of said guide rods 18, 19 is a bearing 21 through which the rod 11 carrying the bottle seat 10 passes. The upper ends of the guide rods 18, 19 are also secured to the lugs 10 formed on the bearing 21.

Arranged around the fixed lower part of the framework of the machine is the cam 17 as seen in Figures 1 and 4, against which engages the roller 16 mounted on the upper part 13 of the 15 cross-head.

The development of the cam 17 as will be seen in Figure 4 is such that a fairly rapid rise is given to the bottle seat 10 consistent with smooth working and also a fairly sharp descent to that part 20 of the cam 17 when the filled bottle is removed and an empty one placed on the machine.

In order to accommodate for any slight variation in the heights of the bottles and to provide for a good seal between the mouth of the bottle 25 and the filling head 22, Figure 1, during the filling operation, provision is made by means of the split cross-head to provide for this.

Upon the mouth of the bottle which is positioned on the seat 10 engaging the filling head 30 22 a further slight movement is permitted by the cross-head being formed of the two parts 12 and 13. This movement of the cross-head may be necessary before the cross-head reaches the highest part of the cam 17. The rod 11 carrying the bottle seat 10 being connected to the lower part 12, which is connected to the part 13 of the cross-head carrying the roller 16 which engages the cam 17 being connected together by the tension springs 14, so that after the bottle mouth is 40 seated, a further slight movement of the upper part 13 of the cross-head can take place against the resistance of the tension springs 14. The part 13 of the cross-head is able to move independently of the part 12 on the guide rods 18, 19. 45

Upon the mouth of the bottle being sealed on the filling head 22 provision is made for locking the bottle seat 10 in its raised position as seen in Figure 3 during the filling operation and this is effected by means of a pivoted hook 23 mounted 50 on the frame of the machine adjacent to the guide rods 18, 19. On the opposite side of the cross-head to the roller 16 is a pin 24 which strikes the pivoted hook 23 during the upward movement of the bottle seat 10, after which the hook 55

23 swings under the pin 24 and holds the bottle seat 10 in its raised position until the completion of the filling operation.

5 The pivoted hook 23 is secured to a spindle 25 on the inner end of which is mounted a lever 26; the object of this lever 26 is to provide means for unfastening the hook 23 which retains the bottle seat 10 in this raised position during the filling operation.

10 Mounted on the fixed base 27 of the machine on a suitable support is a cam 29 against which the lever 26 connected to the bottle seat retaining hook 23 engages after the filling operation is completed, to disengage said hook 23 from the pin 24 15 so as to permit of the bottle seat 10 being lowered for the removal of the bottle and the replacement of another bottle on said seat.

I claim:—

20 1. In bottle motion mechanism for rotary bottle filling machines the combination of a bottle seat, a rod on which said seat is mounted, a cross-head connected to said rod, a second cross-head resiliently connected to the first cross-head and being capable of movement independently of the first cross-head, guides in which said cross-heads operate and means mounted on the second cross-head which engages a cam to operate the bottle seat.

25 2. In bottle motion mechanism for rotary bottle filling machines, the combination of a bottle seat, a rod on which said seat is mounted, a cross-head connected to said rod, a second cross-head resiliently connected to the first cross-head and being capable of movement independently of the first cross-head, guides in which said cross-heads operate and a roller mounted on the second cross-head which engages a cam to operate the bottle seat.

30 3. In bottle motion mechanism for rotary bottle filling machines, the combination of a bottle seat, a rod on which said seat is mounted, a cross-head connected to said rod, a second cross-head resiliently connected to the first cross-head and being capable of movement independently of the first cross-head, guides in which said cross-heads operate, a roller mounted on the second cross-head part which engages a cam to operate the bottle seat and means for retaining the cross-heads in their raised position during the filling operation.

35 4. In bottle motion mechanism for rotary bottle filling machines, the combination of a bottle seat, a cross-head member connected to

5 said bottle seat, a second cross-head member resiliently connected to the first cross-head, guides in which said cross-heads operate, means mounted on the second cross-head for engaging a cam to operate the bottle seat, means for retaining the cross-heads in their raised position during the filling operation and means for releasing the cross-heads from their raised position at a predetermined moment.

10 5. In bottle motion mechanism for rotary bottle filling machines, the combination of a bottle seat, a rod on which said seat is mounted, a cross-head member connected to said rod, a second cross-head member resiliently connected to the first cross-head and being capable of movement independently of the first cross-head, guides in which said cross-heads operate, a roller mounted on the second cross-head which engages a cam to operate the bottle seat, a pivoted hook which engages a projection on the cross-head for retaining the cross-heads in their raised position during the filling operation and means which engage said pivoted hook at a predetermined moment to cause the hook to disengage the cross-head and release same.

15 6. In bottle motion mechanism for rotary bottle filling machines, the combination of a bottle seat, a rod on which said seat is mounted, a cross-head connected to said rod, a second cross-head resiliently connected to the first cross-head and being capable of movement independently of the first cross-head, guides in which said cross-heads operate, means mounted on the second cross-head which engages a cam to operate the bottle seat and means for retaining the cross-heads in their raised position during the filling operation.

20 7. In bottle motion mechanism for rotary bottle filling machines, the combination of a bottle seat, a rod on which said seat is mounted, a cross-head connected to said rod, a second cross-head resiliently connected to the first cross-head and being capable of movement independently of the first cross-head, guides in which said cross-heads operate, means mounted on the second cross-head which engages a cam to operate the bottle seat, means engaging the second cross-head for retaining the cross-heads in their raised position during the filling operation and means which engage the retaining means at a predetermined moment to cause the retaining means to disengage the cross-head and release same.

25 JAMES CHIGNELL.
